ROBERT CLARK, OF BRIDGEPORT, CONNECTICUT, ASSIGNOR TO BRIDGEPORT BRASS COMPANY, OF BRIDGEPORT, CONNECTICUT, A CORPORATION OF CONNECTICUT.

SINK-DRAIN.

1,224,712.

Specification of Letters Patent.

Patented May 1, 1917.

Application filed August 22, 1914. Serial No. 858,147.

To all whom it may concern:

Be it known that I, ROBERT CLARK, a citizen of the United States, residing in the city of Bridgeport, county of Fairfield, and State of Connecticut, have invented certain new and useful Improvements in Sink-Drains, of which the following is a full, clear, and exact description.

This invention relates to a drain or waste fixture, especially applicable to kitchen sinks, but my improvements are not limited to this particular application.

The primary object of the invention is to provide a simple, efficient drain fixture, in which the strainer may be very readily inserted into, and removed from, the outlet bushing or shell in the sink bottom, and wherein an ordinary stopper of rubber, or the like, may be readily substituted for the strainer when it is desired to fill the sink with water. It is also proposed to furnish a fixture of the type indicated in which the locking of the strainer in operative position, and its removal from operative position, are facilitated by the use of a bayonet joint of special form. It is further proposed to provide a drain fixture in which a bayonet joint for locking a strainer in position in the mouth of the bushing does not interfere in any way with the use of an ordinary rubber stopper, when the strainer is removed.

To these and other ends, the invention consists in the novel features and combinations of parts to be hereinafter described and claimed.

In the accompanying drawing,

Figure 1 is a fragmentary side elevation of a drain fixture embodying my improvements;

Fig. 2 is a top plan view of the same, showing the strainer locked in position in the shell or bushing;

Fig. 3 is a section on line 3—3 of Fig. 2, showing the locked position of the strainer;

Fig. 4 is a section similar to Fig. 3, but with the sectional part of the strainer turned to a position to release and elevate the strainer;

Fig. 5 is a side elevation of the strainer, detached; and

Fig. 6 is a section similar to Fig. 3, showing an ordinary rubber stopper fitted in the bushing in place of the strainer.

Referring to the drawing, 10 is an outlet bushing, cup, shell or plug, adapted to be secured in the usual manner in an opening in the bottom of the sink, and having the usual substantially horizontal annular flange 11, adapted to overlie the bottom wall of the sink around the opening formed in the latter. A nut 10^a, engaging the screw threads 12 on the exterior of the bushing, is adapted to clamp the bushing in place, and the lower end of the bushing has secured thereto in any suitable manner the customary waste pipe 13, as shown in Fig. 1. This bushing is adapted to receive a strainer 14 (Fig. 5) which may be locked in the upper end of the same, with its upper surface approximately flush with the flange 11. In the form shown, the strainer 14 is adapted to be accommodated in a special seat 15, formed at the upper part of the bushing or shell, for which purpose the upper end portion of the bushing is made of greater diameter than the lower portion. The wide upper portion is connected with the relatively narrow lower portion by means of an approximately horizontal wall 16 forming a shoulder to seat the annular vertical wall 14^a with which the strainer is provided. By preference, the plug or bushing will be made of sheet metal, and the shoulder 16 will be formed by a suitable drawing operation.

In the embodiment which I have selected for illustration, the bayonet joint for locking the strainer 14 in the seat 15 of the bushing is constructed as follows: The wall of the upper, wider portion of the bushing is provided with a series of inwardly disposed projections or teats 17. In the form shown, these projections or teats 17 are three in number, but of course this is not essential, and they are formed by displacing the metal of the bushing wall in an inward direction, but this likewise is not always essential. In any event, the teats or projections are relatively shallow, and merge into the side wall of the bushing very gradually, for a purpose hereinafter pointed out. The depending annular side wall 14^a of the strainer 14 is provided with a plurality of notches 18 adapted to coöperate with the respective projections 17 in such a manner as to form a bayonet joint, so that the strainer may be locked in the bushing in an obvious manner,

In locking the strainer, the latter is given a partial rotation or turning movement relative to the plug or bushing, so that after the mouths of the notches 18 pass over the respective projections 17, the strainer may be turned to engage the projections in the closed ends of the notches, whereby upward displacement of the strainer is prevented. To release the strainer, the latter is turned 13 in the opposite direction until the mouths of the notches come into register with the respective projections 17, after which the strainer may be readily lifted out of place.

Furthermore, the bayonet joint is preferably so constructed that it is effective in pulling the strainer down into its seat when the strainer is applied. Moreover, what is more important, the bayonet joint is preferably so constructed that when the strainer 20 is partially turned to release the same, said strainer is automatically lifted to a certain extent, so that its upper surface will be raised substantially above the level of the sink bottom, thus facilitating the removal of 25 the strainer. In order to effect these ends, each of the notches 18 is slanted with respect to the vertical, so as to provide an upper inclined edge 18^a, and a lower inclined edge 18^b. When the strainer is in the released position shown in Fig. 4, and is turned clockwise, the lower inclined surface 18^b, by engaging the corresponding projection 17, pulls the strainer down into its seat 15 as the strainer is turned to engage the 30 projections in the closed ends of the notches. This locks the strainer, as shown in Fig. 3, and in this position, each projection or teat 17 engages a relatively enlarged seat 18^c at the closed end of the corresponding notch. When it is desired to unlock the strainer, 35 the same is turned in a counter-clockwise direction, whereupon the upper inclined wall 18^a of each notch will ride on the corresponding projection 17 in such a manner as to raise the strainer relative to the bushing, as shown in Fig. 4. When the strainer 40 is in the position for each notch 18 to pass clear of the corresponding teat or projection, the upper surface of the strainer will be considerably elevated relative to the 45 bottom of the sink, and thus the removal of the strainer from the bushing is very much facilitated.

For the purpose of permitting the necessary turning movement of the strainer, the latter is preferably provided with a diametrical slot 19, into which a knife, or other tool, may be readily inserted. By inserting the knife in the slot 19, and turning the strainer in the proper direction, the latter 50 may be either locked or released.

Preferably the strainer will be formed of a sheet metal plate, having a plurality of perforations in its upper surface, as shown, 55 the upper portion being integral with the

downturned side wall 14^a, but in certain aspects of the invention this is not essential.

When it is desired to fill the sink, an ordinary rubber stopper 20 may be substituted for the strainer 14. The stopper 20 will fit 70 the seat 15 when the strainer is removed, as shown in Fig. 6, and the yielding nature of the stopper will permit it to conform very closely to the small teats or projections 17 on the inside surface of the seat 15, so that 75 there will be no leakage. By preference, the side wall of the seat 15 will have a very slight bevel or taper, as shown, but this is not necessary in all cases.

It will be observed that the inwardly directed shoulder 16 underlies the stopper or the strainer disk when it is inserted into the seat 15. The peripheral wall or other depending portion on the strainer disk is adapted to engage the surface of the stopper 85 seat above and in line with the shoulder, the construction preferably being such that when the depending portion on the periphery of the strainer disk is substantially in contact with the shoulder 16, the upper surface of the strainer disk is substantially flush with the lateral flange on the bushing. With this construction the bayonet lock or its equivalent can be dispensed with in some cases if desired, in which event the shoulder 95 will hold the strainer disk in the proper position vertically with respect to the bushing.

By the construction described, the drain fixture may be produced very inexpensively from sheet metal and yet it is strong and 100 durable, and presents the advantage of permitting the substitution of a radially insertible and removable strainer for an ordinary stopper or plug, and vice versa. The mere turning of the strainer relative to the 105 projections on the bushing raises and lowers it on its seat, and yet the construction is such that an ordinary rubber stopper will readily fit the bushing without leakage when the strainer has been taken out.

I do not claim broadly herein the combination of a bushing adapted to extend through an opening in the bottom of the sink, said bushing having a smooth substantially upright seat at the upper end or 110 mouth thereof adapted to make water tight contact with an ordinary plug or stopper having a beveled seating surface, a strainer adapted to fit the upper portion of said stopper seat when the plug or stopper is removed, said strainer being of a diameter substantially equal to the maximum diameter of the stopper seat, means for detachably engaging said strainer with a part 115 of the bushing to secure the strainer detachably in position, and a laterally projecting flange on the upper end of the bushing which overlies the bottom wall of the sink around the opening in the latter, and positions the bushing with respect to the sink 120

when the stopper is in use as well as when the strainer is in use, as claimed in my application Serial No. 817,916.

Without limiting myself to the construction shown, I claim:

1. In a drain fixture such as described, the combination of a bushing having a laterally projecting flange on the upper end thereof, a nut engaging said bushing to clamp said

10 flange against the upper surface of the sink bottom, said bushing having a seat at the upper end or mouth thereof provided with a substantially smooth surface to receive an ordinary plug or stopper, a strainer disk of

15 a diameter substantially equal to the diameter of the upper portion of said stopper seat, and means for detachably securing said strainer in said seat without interfering with a water tight fit of the plug or stopper in

20 said seat when said plug or stopper is substituted for the strainer, said strainer-securing means being so constructed that the strainer is released from the bushing, for removal, by turning the strainer in said seat;

25 substantially as described.

2. In a drain fixture for sinks and the like, the combination of a bushing having a laterally projecting flange on the upper end thereof, adapted to overlie the bottom wall

30 of the sink around the opening in the latter, a nut to clamp the said flange against the upper surface of the sink bottom, said bushing having a seat at the upper end or mouth thereof, provided with a substantially

35 smooth surface to receive an ordinary plug or stopper, a strainer disk of a diameter substantially equal to the diameter of the upper portion of said stopper seat, a depending peripheral wall on said strainer disk adapted

40 to fit the smooth surface of said stopper seat, and means for detachably securing said strainer in said seat without interfering with a water tight fit of the plug or stopper in said seat when said plug or stopper is

45 substituted for the strainer; substantially as described.

3. In a drain fixture for sinks and the like, the combination of a bushing having a laterally projecting flange on the upper end thereof, adapted to overlie the bottom wall

50 of the sink around the opening in the latter, means carried by the bushing for clamping said flange against the upper surface of the sink bottom, said bushing having a seat at

55 the upper end or mouth thereof to receive an ordinary plug or stopper, the surface of said stopper seat being substantially smooth throughout its area so as to make a water tight fit with the stopper, a strainer disk

60 adapted to fit the upper portion of said stopper seat, a down-turned peripheral wall on said strainer disk adapted to fit within the smooth surface of said stopper seat, and means for detachably securing the strainer

65 in said stopper seat without interfering with

the water tight fit of the stopper in said seat when it is substituted for the strainer, said strainer securing-means including small teats or projections on the seat surface merging gradually into the smooth portion of said surface, and coöperating with notches in the depending wall of the strainer, said notches so formed that the strainer is raised and lowered as it is turned on its axis; substantially as described.

4. In a drain fixture for sinks and the like, the combination of a bushing adapted to extend through an opening in the bottom of

80 the sink and having exterior screw threads for a nut adapted to clamp the bushing in

place in the sink bottom, a lateral flange projecting horizontally from the upper end of

85 said bushing to overlie the bottom wall of the sink around the opening in said wall, said bushing having a smooth, substantially

upright seat at the upper end or mouth thereof to make water tight contact substantially throughout its area with an ordinary plug or stopper having a slightly bevelled seating surface, a strainer disk of a

90 diameter substantially equal to the diameter of the mouth of the bushing, and means for detachably engaging said strainer disk with a part of the bushing to secure the strainer

95 detachably in said seat when the stopper is removed, said engaging means being so constructed that the strainer is raised and lowered as it is turned in said seat; substantially

as described.

5. In a drain fixture for sinks and the like, the combination of a bushing, having a laterally projecting flange on the upper end thereof, adapted to overlie the bottom wall of the sink around the opening in the latter; said bushing having a seat at the

100 upper end thereof with a smooth surface to receive an ordinary plug or stopper with a water tight fit, a strainer insertible into said seat when the stopper is removed, and means for securing said strainer in said seat, such

105 that the strainer is raised and lowered as it is turned on its axis, without interfering with the water tight fit of the stopper in

110 said seat when it is substituted for the strainer, said securing-means including

115 small teats or projections on the surface of the combined stopper and strainer seat located beneath the upper margin of said seat, and adapted to coöperate with notches in the strainer; substantially as described.

6. In a drain fixture for sinks and the like, the combination of a bushing having a laterally projecting flange on the upper end thereof, a nut on the bushing to clamp

120 said flange against the upper surface of the sink bottom, said bushing having a substantially smooth upright seating surface at the

125 upper end or mouth thereof to receive an ordinary plug or stopper, a strainer disk of a diameter substantially equal to the diameter

130

- of the upper portion of the stopper seat adapted to be freely inserted into and removed from said stopper seat at any time when the stopper is removed, a wall depending 5 from that portion of the strainer disk which is of maximum diameter, and means for detachably securing said strainer in said seat without interfering with a water tight fit of the plug or stopper in said seat when 10 said plug or stopper is substituted for the strainer, comprising means for connecting said depending wall with the bushing, such that the strainer is locked and released by a turning movement thereof; substantially as 15 described.
7. In a drain fixture such as described, the combination of a bushing having a laterally projecting flange at the upper end thereof, means for clamping said flange 20 against the upper surface of the sink bottom, said bushing having a substantially smooth upright seat at the upper end or mouth thereof to make water tight contact substantially throughout its area with an ordinary plug or stopper having a slightly 25 beveled seating surface, a strainer adapted to fit within said stopper seat, and means for detachably securing said strainer in said seat without interfering with a water tight fit of the plug or stopper in said seat when 30 said plug or stopper is substituted for the strainer, said strainer-securing means so constructed and arranged that the strainer is locked and released by turning it in said 35 seat; substantially as described.
8. In a drain fixture for sinks and the like, the combination of a bushing having a laterally projecting flange at the upper end thereof, means for clamping said flange 40 against the upper surface of the sink bottom, said bushing having a substantially smooth upright seat at the upper end or mouth thereof to make water tight contact substantially throughout its area with an ordinary plug or stopper having a slightly 45 beveled seating surface, the bushing being of reduced diameter closely beneath said stopper seat to present an inwardly projecting shoulder, a strainer disk adapted to fit 50 within said stopper seat in place of said stopper, and means for detachably supporting said strainer disk in said seat without interfering with a water tight fit of the stopper in said seat when it is substituted 55 for the strainer disk, said strainer disk-supporting means comprising a depending por-

tion on the periphery of said disk adapted to engage the surface of said stopper seat above and in line with said shoulder when the strainer is in the operative position; substantially as described. 60

9. In a drain fixture for sinks and the like, the combination of a bushing adapted to extend through an opening in the bottom of the sink and having exterior screw threads for a nut adapted to clamp the bushing in place in the sink bottom, a flange projecting laterally from the upper end of said bushing to overlie the bottom wall of the sink around the opening in said wall, said bushing having a substantially smooth upright seat at the upper end or mouth thereof to make water tight contact substantially throughout its area with an ordinary plug or stopper having a slightly beveled seating surface, a strainer disk of a diameter substantially equal to the diameter of the mouth of the bushing adapted to fit within said stopper seat when the stopper is removed, said bushing having a shoulder below and in close proximity to said stopper seat, and a depending portion on the periphery of said strainer disk adapted to engage the surface of said stopper seat and of such depth as to lie wholly above said shoulder when the strainer is substantially flush with said lateral flange; substantially as described. 70

10. In a drain fixture for sinks and the like, the combination of a bushing adapted to extend through an opening in the sink bottom, said bushing having a substantially smooth seat at the upper end or mouth thereof adapted to make water tight contact with an ordinary plug or stopper, a strainer disk adapted to fit said stopper seat when the plug or stopper is removed, means for detachably engaging said strainer disk with a part of the bushing to hold said disk detachably in position, an outwardly projecting flange on the upper end of the bushing, said bushing of reduced diameter immediately below said seat so as to present an inwardly projecting shoulder which underlies the stopper or the strainer disk when it is inserted into said seat; substantially as described. 90

In witness whereof, I have hereunto set my hand on the 17th day of August, 1914.

ROBERT CLARK.
